(57) **CLAIM**

I claim the ornamental design for a closure strip for a bodysuit, as shown and described.

DESCRIPTION

FIG. 1 is a front elevational view of a closure strip for a bodysuit showing my new design, the side and rear portions thereof that are not shown being disclaimed, one end portion of a strip closure material on the inside of a flap of a leg portion thereof being shown, an opposite end portion of the strip of closure material being a mirror image and, therefore, not shown, the environment on a torso portion thereof to receive the one end portion of the strip of closure material being shown in dashed lines to show better the arcuate shape of the strip closure material.

The design is characterized by the strip of closure material on the leg portion of the bodysuit garment on the inside of a flap that progresses from the rear to the front of the leg portion for releasably adhering to the outside of the front of the torso portion, the strip of closure material being at an end margin of the flap of the leg portion for adhering at a leg-portion margin of the torso portion.

The broken line showing of the bodysuit is for illustrative purposes only and forms no part of the claimed design.
